inventors } L W Taylor
Chas. S. Lilley # United States Patent Office.

ROBERT R. CAMPBELL, OF LOWELL, MASSACHUSETTS, ASSIGNOR TO
LOWELL MANUFACTURING COMPANY, OF SAME PLACE.

Design No. 4,871, dated May 9, 1871.

DESIGN FOR A CARPET-PATTERN.

The Schedule referred to in these Letters Patent and making part of the same.

all whom it may concern:

Be it known that I, ROBERT R. CAMPBELL, of the
y of Lowell, county of Middlesex and State of Massa-
usetts, have invented and produced a new and orig-
nal Design for a Pattern to be Inwrought into Two
Three-ply, Ingrain, and other Carpeting in such
lors as may be desired; and I do hereby declare
at the photographic prints accompanying this specifi-
cation do give and convey, to any one skilled in the
t of carpet-weaving, a more definite and thorough
scription of the nature of my invention than it is in
e power of language otherwise to convey, and are
fficient to enable any one skilled in the art of carpet-
aving to use my invention.

Claim.

What I claim as my invention, and desire to secure
by Letters Patent, is—

The configuration of the design hereunto annexed
when made by being inwrought into two or three
ply, ingrain, or other carpeting in the form simila
to the photographic prints accompanying this specifi
cation.

R. R. CAMPBELL.
